UNITED STATES PATENT OFFICE.

MARTIN C. KESSLER, OF DENVER, COLORADO, ASSIGNOR TO THE KESSLER MOTOR COMPANY OF DENVER, COLORADO.

EXPLOSIVE-ENGINE.

1,234,039.

Specification of Letters Patent. Patented July 17, 1917.

Application filed August 31, 1907. Serial No. 390,942.

To all whom it may concern:

Be it known that I, MARTIN C. KESSLER, a citizen of the United States, residing at Denver, in the county of Denver and State 5 of Colorado, have invented certain new and useful Improvements in Explosive-Engines, of which the following is a specification.

My invention relates to an improvement in explosive engines of the fourcycle type, 10 or that character of engine in which the explosion takes place every second or alternate rotation of the crank shaft, and in which the spent gases and products of combustion arising from the explosion of the charge 15 are expelled during the succeeding stroke of the piston following each power stroke, a new supply or charge of explosive mixture being drawn into the cylinder with the stroke following the exhaust stroke, which 20 charge is compressed by the piston on the next succeeding stroke at the end of which the explosion takes place.

In a former application filed by me September 17, 1906, Serial No. 334,926, I disclosed an explosive engine having certain 25 characteristics which I will not specify at this point in detail, but among those characteristics were the fact that the air inlet port for supplying air to the crank case or 30 compression chamber, and the discharge port through which the compressed air is issued into the cylinder after compression, were both controlled at times by the piston.

This present invention differs from my 35 former invention in this respect, namely that the piston has no direct control of either the air inlet or outlet ports, although in other respects I have disclosed in the present invention many of the features of my former invention.

The object of this invention, therefore, is to provide means for completely clearing out the products of combustion known as carbonic acid gas from the working cylinder 45 or cylinders, if more than one are employed, after each working stroke, thus leaving the combustion chamber always full of fresh air after each exhaust, regardless of the amount of charge taken in from the main intake of the cylinder; and a further object 50 is to augment the charge taken in through the carburetor as may be required to attain the greatest degree of efficiency.

Hence my present invention comprises

means for compressing air either in a compression chamber or in the crank case, with each inward stroke of the piston, together with means for regularly liberating this full volume of compressed air at the end of every alternate inward stroke of the piston into 55 the cylinder for the purpose of completely scavenging it of all exhaust products, and means within the control of the operator for regulating the discharge of compressed air into the cylinder with each intermediate 60 alternate instroke as an auxiliary means for aiding and increasing the charge when the engine is running under maximum power, or for cutting off this compressed air supply entirely with such intermediate stroke, if 65 it is not required.

This invention still further consists in certain novel features of construction and combinations of parts which will be hereinafter described and pointed out in the claims. 75

In the accompanying drawing:

Figure 1 is an entire vertical section.

Fig. 2 is a detail showing the tapering cam for operating the valve.

Fig. 3 is a view in end elevation, and 80

Fig. 4 is a section through the cam 24 and connected parts.

The engine illustrated is of the fourcycle type, and the crank case is used as a compression chamber, and a single cylinder only 85 is shown.

A represents the cylinder of the engine, 1 is the crank case, 2 is the crank journaled within the case, and 3 indicates the piston with the usual connecting rod 4 extending 90 therefrom to the crank in the crank case.

The customary clearance chamber 5 is formed at the outer end of the cylinder, an intake valve 6 admits the supply of carbureted air, and an exhaust valve 7 regulates 95 the exhaust from the cylinder. The usual sparker 8 is provided at a convenient point for exploding the charge at the required intervals.

An air inlet port 9 is formed at some convenient point in the crank case for the introduction of air into the latter, this port being operated and controlled in any approved manner. A by-pass 10 leads from the crank case 2 to the outer end of the 105 cylinder.

The provision for discharging air from the crank case into the cylinder, and its

control will now be described. In the present drawing only one method of controlling the air is illustrated as a means of exemplifying a feasible plan of carrying out the broad idea of this invention. A valve case 12 is secured to the outer end of the cylinder in any convenient manner; it being chambered out to communicate with the by-pass 10 and the end of the cylinder. This valve case is provided with a valve seat 14. A valve 15 is adapted to control this by-pass 10, it being in position to normally seat itself on the seat 14 when not otherwise prevented. The valve is guided by the valve rod 16 passing through the counter-bored boss 17, and an expansion spring 18 tends to seat the valve at all times. A lever 19 fulcrumed on the post 20 is arranged with one end in position to engage the outer end of the stem 16, and the rod 21 is adapted to slide in and out through a box 22.

Although the expansion spring 18 always tends to close this valve 15, nevertheless the opening of the valve at predetermined intervals is always under positive control. This may be accomplished in different ways, one only of which I have illustrated. This consists of a cam 24 keyed to slide on a cam shaft 25 which latter is preferably adapted to make one complete revolution to two revolutions of the crank shaft. One side *a* of this cam is straight, and the opposite side *b* is tapering. The straight side *a* of the cam opens the valve at the end of every expansion stroke for the purpose of scavenging. The tapering side *b* of the cam is for the purpose of opening the valve, at the end of the intake stroke, a greater or less degree, accordingly as the cam 24 is pushed in or out, it being normally held out by a rod 26, in which position the smaller end of the cam is in contact with the rounded inner end of the rod 21.

When running under normal conditions, therefore, the valve 15 is open near the end of the instroke of the piston following each explosion. To augment the intake of air the cam 24 is forced inward a greater or less degree according to the quantity of air desired to augment the normal intake charge, this being varied and regulated by the degree to which the cam is forced in. When slid inward its entire length, the full crank case compression is discharged into the cylinder in turn for scavenging, and then for augmenting. In this way not only does scavenging take place as heretofore explained at the completion of the alternate instroke of the piston, but also air is discharged into the cylinder with every instroke of the piston from the crank case or compression chamber to supplement the regular volume of charge drawn in from the carburetor with each alternate instroke.

of the piston, so that when the engine is running under full volume, and more charge is required than the inlet valve can supply, the volume of charge is augmented, thereby greatly increasing the power of the engine. The volume of air for this purpose is therefore entirely within the control of the operator by simply adjusting the cam 24, for this valve may be held open ever so little, full open, or at any intermediate point in accordance with the auxiliary supply of air required.

To recapitulate, it might be stated that the present invention differs from my former application previously referred to mainly in the location of the air inlet into the crank case or compression chamber and the discharge of compressed air into the outer end of the cylinder, also in the cam for operating the valve, or in other words, the piston in the present invention has no direct control upon the inflow and the discharge of the air, whereas in my former application, I disclosed means whereby the piston controlled both to a greater or less degree.

Having fully described my invention, what I claim as new and desire to secure by Letters Patent is:—

1. The combination with an engine cylinder having an air inlet port, of a piston, a compression-chamber, a by-pass leading from the compression-chamber to the port, a valve for said port, and means actuated by the engine for opening and closing said valve variable amounts on different strokes of said piston to augment the charge within said cylinder, said means containing an element for controlling the extent of movement of said valve.

2. The combination with a cylinder having an air inlet port, of a piston, a compression-chamber, a by-pass leading from the compression-chamber to the port, a valve for said port, means for opening and closing said valve a predetermined amount on certain strokes of the piston, and means for opening and closing said valve a variable amount on the other strokes of said piston.

3. The combination with a cylinder having an air inlet port, of a piston, a crank-case, a by-pass leading from the crank-case to the port, a valve for said port, common means for opening and closing said valve a predetermined amount on certain strokes of the piston and for opening and closing said valve a variable amount on the other strokes of said piston.

4. The combination with a cylinder having an air inlet port, of a piston, a crank-case, a by-pass leading from the crank-case to the port, a valve for said port, common means comprising a shiftable tapering cam for opening and closing said valve a predetermined amount on certain strokes of the

piston and for opening and closing said valve a variable amount on the other strokes of said piston.

5. In an explosive engine, the combination with a cylinder, crank-case and piston, the engine being provided with an induction port adapted to supply air to the crank-case and having a by-pass leading from the crank-case to the cylinder at a point beyond the reach of the piston, means for discharging air from the crank-case into the cylinder with each alternate revolution of the crank-shaft, and adjustable means for opening and closing the valve whereby a variable quantity of air may be discharged into the cylinder from the crank-case with the remaining revolutions of the crank-shaft.
10. In an explosive engine, the combination with a cylinder, compression-chamber, crank-shaft, and piston, the engine being provided with a by-pass leading from the compression-chamber which discharges into the cylinder at a point beyond the reach of the piston, said by-pass having a valve seat therein, a valve which is opened and closed with every alternate instroke of the piston and normally closes with the remaining inward strokes of the piston, said valve being within the control of the operator whereby the latter may be opened a greater or less degree and closed with certain strokes of the engine.
15. In an explosive engine, the combination with a cylinder, a compression cham-

ber, and piston, the engine provided with a by-pass leading from the compression chamber to the cylinder at a point beyond the reach of the piston, a valve therein, a lever for operating the valve, a rod connected with the lever, a cam for operating the rod, and means within the control of the operator for regulating the position of the cam for controlling said valve.

20. In an engine in which air is compressed in a compression chamber, means for controlling and varying the volume of air delivered from said chamber to the engine cylinder with each alternate revolution of the crank shaft, a valve operated by said means and a shiftable tapering cam for regulating and operating the valve.

25. In an engine in which air is compressed in a compression chamber, means for controlling and varying the volume of air delivered from said chamber to the engine cylinder with each alternate revolution of the crank shaft, a valve operated by said means, a shiftable tapering cam for regulating and operating the valve, and a cam shaft upon which the cam is slid able and with which it rotates.

30. In testimony whereof I affix my signature in presence of two witnesses.

MARTIN C. KESSLER.
